CHILD'S GARMENT

Max I. Lehman, New York, N. Y.

Application April 11, 1944, Serial No. 530,490

6 Claims. (Cl. 2-80)

This invention relates to a child's garment.

An object of this invention is to provide a multi-use child's garment which is simple in construction so that it may be readily cleaned and ironed. The garment embodies a pair of trunks, a waist, suspenders, and a bib, and in one form all of these elements may be coupled together. In a second use or combination of the garment, the suspenders and bib may be left off, and in a third use or combination, the trunks may be combined with only the suspenders. A fourth use or combination may be formed by combining the trunks, bib and suspenders, omitting the waist, and in a fifth use the trunks may be used alone, being supported by a belt.

The garment may be made from any desired color combinations, or in solid colors, and the various elements making up the complete combination are detachably coupled together by means of buttons or other suitable fastening devices.

With the foregoing objects and others which may hereinafter appear, the invention consists of the novel combination, construction and arrangement of parts as will be more specifically referred to and illustrated in the accompanying drawings wherein there is disclosed an embodiment of the invention, but it is to be understood that changes, modifications and variations may be resorted to which fall within the scope of the invention as claimed.

In the drawings:

Figure 1 is a detail front elevation of a child's garment constructed according to an embodiment of this invention.

Figure 2 is a detail rear elevation of the garment.

Figure 3 is a sectional view taken on the line 3-3 of Figure 1.

Figure 4 is a fragmentary sectional view taken on the line 4-4 of Figure 1.

Figure 5 is a fragmentary sectional view taken on the line 5-5 of Figure 2.

Figure 6 is a fragmentary sectional view taken on the line 6-6 of Figure 2.

Figure 7 is a fragmentary front elevation of the upper portion of the trunks, and

Figure 8 is a fragmentary front elevation of one of the suspender straps.

Referring to the drawings, the numeral 10 designates generally a pair of trunks and the numeral 11 designates generally a waist or shirt which is detachably coupled to the trunks 10. The trunks 10 are provided with pockets 12 at the front thereof and the trunks 10 are also split at the opposite sides and at the upper portions thereof, as indicated at 13. The split portions of the trunks 10 overlap each other and, preferably, the trunks at their upper edges are provided with a relatively deep hem 14. The hem 60

14 is in two sections, including a front section 15 and a rear section 16. The front hem section 15 at the opposite ends thereof is extended to form oppositely extending tabs or tongues 17 which are formed with buttonholes 18. The underlying portion of the rear hem portion 16 is provided with buttons 19 which engage through the buttonholes 18. The trunks 10 are also provided with a plurality of belt loops 20 secured in 10 horizontally spaced relation about the trunks for removably supporting a belt 21 of desired construction.

The trunks 10 at the inner front side thereof has secured thereto an elongated strap 22 which is secured at its lower edge and opposite ends by stitching 23 to the inner side of the trunks 10 thereby forming an upwardly opening channel 24. The trunks 10 at the rear thereof and on the inner side has secured thereto a pair of upwardly 20 extending tabs 25 formed with buttonholes 26. The waist 11 at the front thereof is opened in the usual manner and is formed at the upper portion with lapels 27 and an attached collar 28. The waist 11 may also be provided with one or 25 more pockets 29 at the front thereof, and in order to detachably couple the lower portion of the waist 11 to the upper portion of the trunks 10, the waist 11 is provided with a pair of front buttons 30 and a pair of rear buttons 31. The 30 front buttons 30 engage through buttonholes 32 formed in the channel forming strap 22 and the buttons 31 engage through the buttonholes 26 of the tabs 25.

A pair of suspender straps 33 and 34 which may 35 be formed of fabric are provided at the opposite ends thereof with buttons 35 and 36. The strap 33 at the rear thereof is formed with an elongated opening 37 and the strap 34 is adapted to be threaded through the opening 37, as shown in Figure 2, so that the suspender straps will be disposed in crossed relation at the rear of the garment. Each suspender strap is also provided at the forward end thereof adjacent the forward button 35 with a buttonhole 38. The buttonhole 40 38 is provided so that when the waist is used in combination with the suspenders, the buttons 30 carried by the waist may be extended not only through the buttonholes 32 but also through the buttonholes 38.

Preferably, the forward ends of the suspender straps when used in combination with the waist 11 are disposed in the channel 24. It will of course be understood that if desired the forward ends of the suspender straps may be disposed on the rear side of the strap 22 between the waist and this strap. A bib 39 of substantially truncated triangular configuration is adapted to be mounted on the forward side of the garment. The bib 39 is adapted to engage within the channel 24 as shown in Figure 6. The lower

edges of the bib 39 have secured thereto buttons 40 which are adapted to engage through buttonholes 41 formed through the hem 14. The suspender strap 33 has secured thereto a button 42 which is adapted to engage through a buttonhole 43 formed in the upper portion of the bib 39 and suspender 34 has secured thereto a button 44 adapted to engage through a button-hole 45 formed in the upper opposite edge of the bib 39. The bib 39 is adapted to protect the front of the waist 11 and may be worn with the trunks and the suspenders, or if desired, may be uncoupled therefrom.

The waist 11 is provided with front buttons 46 engaging through buttonholes 47 formed in the rear hem section 16, and the buttons 46 underlie the ends of the front hem section 15. The tabs 17 project beyond the buttons 46 so that when the garment is worn, the waist buttons will be concealed.

The garment hereinbefore described is capable of a number of different combinations, one combination or use being that the trunks 10 may be used as a sunsuit without the shirt, suspenders or bib. The shirt 11 may be coupled with the trunks 10, eliminating the suspenders and bib or the suspenders may be attached and the bib left off. The complete assembly embodies the trunks, waist, suspenders and bib. If desired, the waist may be left off and the trunks supported by the suspenders, either with or without the bib 39. The waist 11 is here shown as having relatively short sleeves, but it will be understood that these sleeves may be of any desired length.

The garment hereinbefore described may be made in either solid colors with the various parts of the same color, or may be made of different colors so as to provide different color combinations.

What I claim is:

1. A garment comprising a pair of trunks, an elongated horizontally disposed strap on the inner side of said trunks at the front thereof, means securing the lower edge and opposite ends of said strap to the upper portion of said trunks, said strap forming an upwardly opening channel at the upper edge of the trunks and said strap having a pair of fastening elements, a waist adapted to fit interiorly of said trunks, securing means carried by the front lower portion of said waist engageable with said fastening elements, a pair of vertically disposed tabs secured to the inner side of said trunks at the rear thereof and having at least one fastening element, and securing means carried by the rear of said waist engageable with the fastening means of said pair of tabs.

2. A garment comprising a pair of trunks, an elongated horizontally disposed strap on the inner side of said trunks at the front thereof, means securing the lower edge and opposite ends of said strap to the upper portions of said trunks, said strap forming an upwardly opening channel at the upper edge of the trunks and said strap having a pair of fastening elements, a pair of suspender straps, one of said suspender straps having an elongated opening at the rear thereof through which the other of said suspender straps is threaded so that the suspender straps will be disposed in crossed relation to maintain the straps in fixed position on the shoulders of the wearer,

securing means at the opposite ends of said suspender straps, a pair of said securing means engageable with said first pair of fastening elements, a pair of vertically disposed tabs fixed to the inner side of said trunks and having at least one fastening element, another pair of said securing means engageable with said latter fastening elements.

3. A garment comprising a pair of trunks, an elongated horizontally disposed strap on the inner side of said trunks at the front thereof, means securing the lower edge and opposite ends of said strap to the upper portion of said trunks, said strap forming an upwardly opening channel at the upper edge of the trunks and said strap having a pair of fastening elements, a waist adapted to fit interiorly of said trunks, securing means carried by the front lower portion of said waist engageable with said fastening elements, a pair of vertically disposed tabs secured to the inner side of said trunks at the rear thereof and formed with at least one fastening element, and securing means carried by the rear of said waist engageable with the fastening elements of said pair of tabs, a pair of suspender straps each having a fastening element adjacent one end thereof, a securing means fixed to said suspender straps adjacent the opposite ends thereof, said trunks having a pair of fastening means at the rear thereof for engaging said latter securing means, said first mentioned waist securing means also engaging with said suspender strap fastening elements, a bib engageable at its lower edge within said channel, correlated fastening means carried by said bib for securing the latter to the outer side of said channel, and correlated fastening means carried by said bib and said suspender straps for securing the upper portion of said bib to said suspender straps.

4. A garment comprising a pair of trunks, the front of said trunks being formed of four pieces of material, comprising two halves stitched together at the center portion thereof, and being cut away at their outer upper edges and an insert adapted to form a portion of the upper outer edge of the front as well as to form a part of the front pockets, a facing at the upper waist line and a plurality of belt straps stitched across the hem formed by said facing, said hem having a plurality of fastening elements, and a bib adapted to be fastened onto said hem by means of securing means on the lower part of said bib, an additional inner hem stitched to the inside of said first hem at the lower portion thereof, said second hem having a plurality of fastening elements adapted to engage securing means attached to a blouse to be worn with said trunks.

5. The garment as set forth in claim 4, a pair of fastening elements at the upper corners of said bib, a pair of suspender straps having securing means centrally of the front thereof adapted to engage with said last fastening elements.

6. The garment as set forth in claim 4, a pair of fastening elements at the upper corners of said bib, a pair of suspender straps having securing means centrally of the front thereof adapted to engage with said last fastening elements, said straps each having a fastening element and securing means at the extreme lower front edge thereof.

MAX I. LEHMAN.
